UNITED STATES PATENT OFFICE

2,598,268

DUCK CALLER

George L. Kendrick, Shreveport, La.

Application December 30, 1947, Serial No. 794,707

5 Claims. (Cl. 46—180)

1

The present invention relates to wind instrument devices for producing tones resembling the calls of birds, and has particular reference to a reed instrument which may be referred to as a duck caller, for reproducing the call of the duck.

An object of the invention is to provide a duck caller having improved tonal quality, which is adjustable as to tone and characterized by improved operating efficiency.

A further object of the invention is to provide a reed wind instrument capable of producing true, clear tones resembling the call of the duck, the tone being adjustable between extremes of fine and coarse tones.

A further object is to provide a duck caller of such construction that the tonal qualities thereof are unaffected by temperature variations which normally modify the vibrational characteristics of the reed.

Yet a further object is to provide a duck caller of simple and inexpensive construction, and which may be assembled and disassembled easily for purposes of parts replacement and cleansing.

Other objects and advantages of the invention will be apparent from the following detailed description thereof taken in connection with the drawings, wherein:

Figure 1 is a perspective view of the device;

Figure 2 is a view in longitudinal cross section;

Figure 3 is a cross-sectional view taken along the line 3—3 of Figure 2; and

Figure 4 is a cross-sectional view taken along the line 4—4 of Figure 2.

In its broadest application, the invention contemplates the provision of a reed wind instrument capable of reproducing tones resembling the call of the duck. Means are provided for anchoring the reed in such manner as to eliminate variation in tonal quality through kinking of the reed, or other defective operation of the reed attributable to variations in atmospheric temperature and humidity normally encountered throughout the hunting season.

Referring to the drawings, the numeral 10 refers to a barrel or case longitudinally bored to provide a chamber 11 extending the length thereof. As shown best in Figure 2, the diameter of the chamber 11 is expanded abruptly to form a shoulder 12 terminating in internally threaded portions 13 of a longitudinally extending wall 14 of the barrel 10.

A plug or cap 15 is provided with an extension 16 threaded externally at 17 for engagement with the internal threads 13 of the barrel extension 14. The plug 15 is provided with a longitudinally

2

extending bore 18, forming a tone chamber. It will be observed that the extension 16 of the plug 15 is appreciably shorter than the barrel extension 14 of the barrel 10, whereby a space 20 is defined between the terminal portions of the extension 16 and the shoulder 12 of the barrel, permitting of pressure-tight assembly of the parts now to be described.

A reed support is indicated generally at 21 and 10 comprises a base 22 round in cross section and of a diameter less than the chamber defined by the extension 14 of the barrel 10, and larger than the inside diameter of the barrel 10. The base 22 is provided with a longitudinally extending 15 member 23 bored to provide a wind tunnel 24 extending through the reed support 21 and opening into the bore 18 of the plug 15, which serves as a tone chamber. The base 22 is slotted at 25 forming a socket just above the wind tunnel 24 to 20 receive the non-vibrating end of a reed 26 removably secured therein by a bushing or wedge 27 preferably formed of rubber or similar material, the reed 26 resting firmly upon an extension 28 forming a solid base therefor. The provision of 25 this solid base 28 for the non-vibrating end of the reed 26 has the important advantage of eliminating tonal variation induced by instability of support provided for the reed, as well as strengthening the entire reed assembly 21. Further, this 30 construction eliminates kinking of the reed characteristically induced by pressure of the bushing 27 or other securing means thereon, when conditions of elevated temperature and humidity prevail.

35 When it is desired to modify the tone produced by the device, this may be accomplished by means of a tone modifier 29 adapted for insertion in the bore 18 of the plug 15. The element 29 preferably may comprise a bushing of 40 resilient material of larger diameter than the bore 18 and capable of compression for insertion therein, such as rubber. To this end, the element 29 is formed with a longitudinally extending bore 30 provided with a radially extending 45 slot 31, permitting of compression of the opposed sides 32 of the element adjacent the slot 31 for purposes of insertion in the bore 18. Release of the compressing force on the sides 32 secures the element 29 in place and ensures the maintenance of the parts in tight fitting relationship, but movable longitudinally relative to each other for purposes of defining a tone chamber for tone adjustment. In the embodiment of the invention shown, if a small tone chamber is defined 50 in the bore 18 by the element 29 and the reed

base 21, a fine tone is produced. As the tone chamber is enlarged by movement of the element 29 outwardly, a coarser tone is produced. Thus, the device may be adjusted to attain maximum effectiveness for operation in all types of hunting terrain and weather conditions.

In assembling the device, the reed assembly 21 is inserted in the barrel 10 so that the base 22 abuts the shoulder 12 of the casing. The plug 15 then is screwed into the barrel 10, positioning the reed assembly firmly in place with a positive pressure. The tone modifying element 29 is then compressed, inserted in the bore 18, and longitudinally adjusted for desired tonal characteristic.

The main component parts of the device may be manufactured from metal, plastics, wood, paper or other satisfactory materials. The device is so formed as to eliminate the production of off tone sounds, and may be adjusted to attain a desired true tone. The duck caller has 20 the further advantage of being small and compact in size.

While the invention has been described with reference to the specific structure shown, obvious modifications in the interrelation of parts and materials employed will be apparent to one skilled in the art. The invention is to be limited in scope only as defined in the appended claims.

I claim:

1. A duck caller comprising a barrel section having a bore extending longitudinally therethrough, said bore having an inlet end and an outlet end and abruptly increasing in diameter to form a shoulder and a bore extension of increased diameter at the outlet end, a base member having an end of greater diameter than the bore and smaller diameter than the bore extension, said base member positioned within the bore with said end against the shoulder, a wind tunnel extending longitudinally through said base member, a reed supported in the base member extending along one side of the wind tunnel, said bore extension being interiorly threaded, a plug having an exteriorly threaded extension thereon engaging the threads of said bore section and pressing the end of the base member against the shoulder to hold it firmly in position, a bore extending through the plug, and a tone modifier longitudinally adjustable in the bore in the plug partially blocking said bore for control of the tone of the caller.

2. A duck caller as described in claim 1 in which the tone modifier comprises a resilient member

normally of slightly larger diameter than the bore in the plug, a radial slot extending longitudinally through the resilient member whereby the resilient member may be compressed for insertion in the bore of the plug.

3. A duck caller comprising a barrel section having a bore extending longitudinally therethrough, said bore having an inlet end and an outlet end, a base member positioned within said bore, a wind tunnel extending longitudinally through said base member, a reed supported at one end in the base member extending along one side of the wind tunnel, the supported end of the reed being towards the outlet end of the bore, a tone modifier adjustable longitudinally in the bore between the base member and the outlet end thereof, said tone modifier partially blocking the bore between the base member and the outlet for controlling the tone of the caller.

4. A duck caller as described in claim 3 in which the tone modifier comprises a resilient member normally of slightly larger diameter than the bore, a radial slot extending longitudinally through the resilient member whereby the resilient member may be compressed for insertion in the bore.

5. A duck caller as described in claim 3 in which the tone modifier comprises a resilient member normally of slightly larger diameter than the bore, a radial slot extending longitudinally through the resilient member whereby the resilient member may be compressed for insertion in the bore, and a bore opening into the slot and extending longitudinally through the resilient member.
